UNITED STATES PATENT OFFICE.

CLARENCE A. SCHUBERT, OF FINDLAY, OHIO.

HANDLING APPARATUS FOR COAL AND THE LIKE.

Application filed April 5, 1922. Serial No. 549,834.

To all whom it may concern:

Be it known that I, CLARENCE A. SCHUBERT, a citizen of the United States, residing at Findlay, Ohio, have invented certain new and useful Improvements in Handling Apparatus for Coal and the like, of which the following is a specification.

Though the mechanism of this invention is designed primarily for the handling of coal, it is adapted also for the handling of gravel, ore, and the like, and among the objects of this invention are to improve upon present methods of handling coal, gravel, ore and the like; to provide means for hoisting coal from approximate ground level to the top of a storage bin or reservoir therefor and place the same in the bin without causing unnecessary breakage of the coal; to provide conveying means for distributing coal and the like to different ones of a plurality of storage reservoirs; to improve upon the mechanism for operating the hoisting bucket; to improve upon the mechanism for carrying the hoisting bucket; to provide appropriate means for indicating the position of the hoisting bucket relatively to certain switches; to provide means for indicating when to empty the hoisting bucket; and such further objects, advantages and capabilities as will later more fully appear.

My invention further resides in the combination, construction and arrangement of parts illustrated in the accompanying drawings, and, while I have shown therein a preferred embodiment, I desire the same to be considered as illustrative only and not as limiting my invention.

In the drawings annexed hereto and forming a part hereof,

Fig. 1 is a broken vertical fragmentary section of a structure embodying my improvements.

Fig. 1^a shows a modified form of track and means for holding the bucket carrier to the track.

Fig. 1^b is a fragmentary view of the hoist showing the application thereto of an indicating mechanism.

Fig. 1^c is an elevation of the indicator shown in Fig. 1^b.

Fig. 2 is an end elevation and Fig. 3 a side elevation of the bucket and carrier shown in Fig. 1.

Fig. 4 is a fragmentary substantially cen-

tral vertical section through the construction shown in Fig. 3.

Figs. 5 and 6 show respectively an end elevation and a side elevation of the jack movable along the track over the storage reservoirs shown in Fig. 1.

Figs. 7 and 8 are respectively side elevation and plan view of a switch used to direct the cars selectively to one track or another.

Referring more in detail to the annexed drawings, numerals 1 and 2 denote two of a series of storage reservoirs or bins adapted to receive coal, gravel, ore or the like. Numeral 3 denotes a transferring track extending across the tops of these reservoirs. Numerals 4 and 5 denote lowering tracks, extending downwardly into the reservoirs to points, more or less close to the bottom thereof, while 6 denotes an elevating track extending from a point near or below the ground level. Numerals 7 and 8 denote means for getting coal or the like into the hoisting and transferring buckets 9, and in the present instance denote a railway track and a chute by means of which the coal or similar substance is transferred to the bucket 9, which bucket is pivotally carried by the car or truck 10. It is customary, though not necessary, in structures of this kind, to provide the storage bins or reservoirs each with a bottom sufficiently elevated from the ground level so that the contents of the bin may be run out of a chute into a delivery truck or the like to be hauled away to points where final delivery is to be made.

Reference will now be had more particularly to Figs. 2, 3, and 4, from which it will be evident that the pivots 11, of the bucket are attached some little distance above the center of gravity thereof, and therefore that the normal tendency of the bucket is to remain in upright position. The truck or car 10, is made up of a pair of substantially triangular end frames connected by transverse bars 12 to hold the sides together. At each of the angles of the truck is a web or gusset to reinforce the angle. Connected to the upper gussets, 13, on a line passing substantially through the center of mass of the bucket and truck is a handle or bail 14, which is pivotally connected to the gussets 13 at 15. The bucket is normally provided with a plurality of apertures 16 in its end.

walls which are adapted to receive stop members 17, which may strike the side members 18 of the frame of the car when the bucket is rotated on its pivots 11. The purpose of these stops will be brought out more in detail hereinafter.

The track on which the car 10 runs may be made of channel iron strips 19 or T-iron strips 20, and the means for holding the car to the tracks will be correspondingly shaped. As shown in Fig. 2, when the channel iron is used a single roller will be pivotally mounted at each corner of the truck and will run in the channel. This will furnish means for preventing either up or down motion, transversely of the track. As will be seen by reference to Fig. 1^a, when the T-iron track is used a pair of rollers will be used at each corner of the truck. These will serve as anti-friction means and means to prevent motion of the car transversely of the track.

A double drum hoisting mechanism, denoted generally by the numeral 21, is provided, and, by means of this, the car may be caused to move along the track and controlled in its movements thereon. Leading from one of the drums of the hoist is a cable 22, which is connected with the bucket 9 at 23, while another cable 24 passes up over a pulley 25 to one drum 26, mounted on shaft 27, carried by the jack 28. Another drum 29 is carried by shaft 27 and around this drum is wound a cable 30, whose free end is connected to the bale 14 at 31.

It will be seen by reference to Fig. 1 that when cable 24 is wound up by the hoisting mechanism 21, it will be unwound from drum 26, and, at the same time, cable 30 will be wound up on drum 29, thereby causing the truck to be pulled up track 6. While this is being done cable 22 is allowed to run slack and will therefore unwind from the hoisting drum. As the car passes the switch 32 (Fig. 1) it will run down the track under the influence of the force of gravity, until it is stopped by cable 30, as shown in the upper right hand dotted position in this figure. From this point on the brake in hoist 21 will be used to permit the unwinding of cable 24 from the hoist and the simultaneous unwinding of cable 30 from drum 29. This will permit the car and bucket to descend more or less slowly into the reservoir until the desired height is reached when the car will be stopped. The other drum of hoist 21 is now rotated to wind up cable 22 which causes the bucket to be dumped as shown in the lower right hand dotted position in Fig. 1. Further winding of this drum will pull the bucket and car back up track 4 over switch 32, and past the crest of track 6, when it will be necessary to apply the brake to the hoisting drum so as to regulate the speed at which cable 24 is allowed to unwind, thereby regulating the speed of the descent

of the bucket. In this way the bucket can be allowed to again descend to loading position as shown in Fig. 1.

A shaft 33, carrying a pulley 34, is pivoted at 35, in the sides of the car. When the bucket 9 reaches the dumping position and cable 22 is pulled to invert the same, this cable comes in contact with pulley 34, and is kept thereby from contact with brace member 12 which prevents it from being roughened and worn out by sliding over the edge of said brace member. When the bucket is dumped, pins 17 come in contact with frame members 18, as stated above, and prevent the bucket from turning over farther than desired. This insures that as the car goes back up the track 4 towards the upper dotted line position at the right, said car would tend to automatically assume its normal upright position. This is prevented, however, by reason of the fact that cable 22 is being pulled on to elevate the car. Therefore, as soon as the tension on cable 22 is released, after the car passes switch 32, the bucket will assume its normal position. The end walls of the bucket may be reinforced in any desired manner as by having bosses formed thereon or having reinforcing plates secured thereto, on the inside, but preference is given to the latter. Holes 16 are then made through the walls and reinforcements and tapped to receive the screw threaded ends of the pins 17. This makes the connection strong enough so that when the pins 17 strike frame members 18 there will be no danger of their being pulled out. It is sometimes desirable to be able to dump the bucket at an intermediate position and it is for this reason that a plurality of holes 16 are provided. For example, if it is desired to have a loading hopper located above the hoist 21, so that material may be loaded into a wagon located between the hoist and reservoir 1, the pins 17 will be put into such openings 16 as will permit the bucket 9 to be inverted when between the two positions shown at the left in Fig. 1.

Any suitable actuating means 38 may be provided for moving and holding the switches 32 up into position, as shown at the right in Fig. 1, or permitting them to assume the lower position shown at the left in Fig. 1. It is obvious that by properly manipulating these switches the bucket 9 may be caused to descend in any one of a series of reservoirs. When the bucket descends to near the level of the coal in the reservoir before it is dumped, there will be less breakage of the coal upon inverting the bucket.

In order to indicate the position of the bucket 9 with respect to loading position shown in Fig. 1, as well as switches 32 and dumping position, certain mechanism is provided which will now be described. Mounted on the frame of the hoist 21 is a bracket

40, which is secured in any suitable manner to a casing of an indicator 41. Extending through the casing is a shaft 42, carrying adjacent one end a gear 43 and having intermediate its ends a worm 44 which meshes with a suitable worm-wheel 45 within the casing. The casing of the indicator 41 is so mounted that the gear 43 engages the gear 46 and is positively driven thereby. It will therefore be apparent that when the hoisting engine 47 drives the gear 46 it will also drive the gear 43 and the pointer 48 carried by the shaft 49, on which is also mounted the gear 50 meshing with gear 51 on the same shaft 15 as gear 45. On the face 52 of the indicator 41 is a mark 53 and a plurality of marks 54. When the pointer 48 is opposite mark 53, it indicates that bucket 9 is in the pit, in the loading position shown in Fig. 1. As the 20 hoist is operated the bucket 9 approaches the first switch 32 and simultaneously the indicator 48 approaches the first indicating mark 54. If it is desired to have the bucket go into the first bin or reservoir, it will then 25 be necessary to see that the switch 32 is so turned that this may take place. If, on the contrary, it is desired that the bucket shall go down into one of the other bins, then it will be necessary to see that the first switch 30 32 is raised into position to direct the truck on to track 3 rather than track 4. It will be clear that with the arrangement shown it will be very easy to know where the truck is with relation to any one of the storage bins or pockets since the pointer 48 will at 35 all times indicate its position with respect to the various switches 32.

When one of the bins 1, 2, etc., is being filled, it is desirable to know where the bucket 9 is in relation to the top of the coal in that particular bin so as to know when to dump the coal by inverting the bucket. This is accomplished by providing an indicator 55 on the ring 56 which is rotatable 40 with respect to the casing of the indicator 41. When one of the bins is being filled, the initial dumping position is determined and the ring 56 is then so set that the indicating point 55 will denote when the bucket 45 is to be inverted. As the bin fills up, it will be necessary to dump the bucket sooner, and the ring 56 will therefore have to be rotated until point 55 indicates the proper dumping 50 position of the bucket, as shown by the approach of pointer 48 to point 55. The setting indicated in Fig. 1^e is for the dumping 55 of coal near the bottom of the fifth bin, whereas, if it were desired to dump near the bottom of the first bin point 55 would be set, probably, near the third indicator 54 and gradually advance toward the first indicator 54 as the bin was filled. It is believed 60 that the operation of the indicator shown in Fig. 1^e will be clear without further description thereof.

It is of course understood that the specific description of structure set forth above, may be departed from without departing from the spirit of my invention as set forth in this specification and the appended claims. 70

Having now described my invention, I claim:

1. In a structure of the character described, an elevating track, a transferring track, a lowering track, said tracks being 75 connected, a transfer bucket, movable on said tracks, and mechanism for moving said bucket back and forth upon said tracks.

2. In a mechanism of the character described, a material transferring mechanism, 80 a storage reservoir for the reception of the material, a track leading down into the reservoir to carry the mechanism down into the same, and means for dumping the material from the mechanism when the same has reached a selected point in the reservoir. 85

3. In an apparatus of the character described, a storage reservoir, a track leading to the top thereof, and from the top down 90 into the interior thereof, a car traveling on said track, a normally upright bucket carried by said car, mechanism for lowering said car into the reservoir and for dumping said bucket at any selected height therein. 95

4. In a mechanical arrangement of the character described, a plurality of storage reservoirs, a track extending across the tops of the reservoirs, a track in each reservoir extending downwardly from the first named track towards the bottoms of the reservoirs, an elevating track, a bucket traveling on said tracks, and means for shifting the bucket from the first named track to any one of the 100 downwardly extending tracks. 105

5. In a structure of the character described, cooperating, elevating, transferring and lowering tracks, a bucket traveling on said tracks, a jack on the transferring track to assist in raising, transferring and lowering the bucket, and mechanism for actuating the bucket on the various tracks. 110

6. In a mechanism of the character described, a transferring device comprising a car and a bucket carried thereby, said bucket being pivoted above its center of gravity upon said car, means on the bucket to engage the car to limit the rotation of the bucket with respect to the car, and means for moving the transferring device, connected to the car. 115 120

7. In a mechanism of the character described, a transferring device comprising a car and a bucket carried thereby, said bucket being pivoted above its center of gravity upon said car, and means for moving the transferring device connected to the car at points on a line passing substantially through the center of mass of the transferring device and load when the bucket is 125 130 loaded.

8. In a structure of the character described, a transferring device comprising a car and a bucket pivoted thereon, said bucket having stops shiftable to different positions to stop the same where desired when it is turned on its pivots to dump the contents of the bucket.
9. In a construction of the character described, a plurality of storage bins, tracks and hoisting mechanism for filling said bins, said hoisting mechanism including a truck carrying a bucket and said tracks including switches for diverting said truck and bucket into one or another of said bins, in combination with an indicator for indicating the approach of the truck to any one of the switches.
10. In a construction of the character described, a plurality of storage bins, tracks and hoisting mechanism for filling said bins, said hoisting mechanism including a truck carrying a bucket and said tracks including switches for diverting said truck and bucket into one or another of said bins, in combination with an indicator for indicating the approach of the truck to any one of the switches, said indicator also indicating when to invert the bucket for emptying the same.
11. In a structure of the character described, a storage bin, bucket mechanism for transferring material from outside the bin into said bin, means for indicating when the bucket has reached dumping position within the bin, and means connected to the bucket mechanism and the indicating means for operating the same by the movement of the bucket mechanism.
12. In a structure of the character described, a storage bin, a bucket, hoisting mechanism for raising the bucket to the top of the bin and letting it down into the same, and means cooperating with the hoisting

mechanism to indicate where the bucket is in the bin with relation to the dumping point in said bin.

13. In a structure of the character described, an elevating track, a transferring track, a lowering track, and a switch to selectively connect the elevating track with the other tracks, in combination with a transfer bucket, movable on said tracks, and mechanism for moving said bucket back and forth upon said tracks.

14. In a material transferring means, tracks for elevating, transporting, and lowering the material, material holding means movable on said tracks to transfer the material, and switches in said tracks to direct the holding means to one or another of the lowering tracks.

15. In material transferring means, tracks for elevating, transporting, and lowering the material, material holding means movable on said tracks, to transfer the material, switches in said tracks to direct the holding means to one or another of the lowering tracks, and means to actuate said switches.

16. In material transferring means, a track for elevating material from a pit, another track connected with the first named track for transferring the material to another location, other tracks capable of being connected with the second named track for lowering the material to a lower position, material holding means movable on said tracks for carrying materials from one place to another, switches associated with said tracks to direct the holding means to one or another of the lowering tracks, and means to actuate said switches.

In witness whereof, I hereunto subscribe my name to this specification.

CLARENCE A. SCHUBERT.
